Primary Examiner—Louis S. Zarfas
Assistant Examiner—Monica A. Weingart(57) **CLAIM**

The ornamental design for a rifle scope cover, as shown and described.

DESCRIPTION

FIG. 1 is a perspective view of a rifle scope cover showing my new design;

FIG. 2 is a top plan view on a reduced scale thereof;
FIG. 3 is a side elevational view thereof, the dashed lines representing the respective endcaps in an alternate open condition, and the opposite side being a mirror image thereof;

FIG. 4 is a bottom plan view thereof;

FIG. 5 is a front end elevational view thereof; and,

FIG. 6 is a rear end elevational view thereof.
